coupling 40 with the vertical shaft 41 of the motor, these two shafts being thus disposed in vertical alignment and being directly connected.

The intake conductor 42 for the pump extends well down into the sump constituted by the lower end of chamber 11. Conductor 42 enters the pump housing 38 on one side, while the discharge from the pump is taken by another conductor 43 which extends up to and is connected with a fitting 44 mounted in the partition 28. In the partition there is a cavity 45 formed in the casting operation. Fitting 44 connects conductor 43 with this cavity. Directly above fitting 44 another fitting 46 is mounted in the partition and serves to connect cavity 45 with an upwardly extending conductor 47 which leads to the intake side of valve 17. Exhaust liquid from valve 17 is transmitted through a conductor 48 which extends downwardly through partition 28 and into the sump, preferably terminating below the normal liquid level therein so as to avoid splash and aeration of the oil.

In order to control the pressure of the liquid delivered by the pump I provide a pressure relief valve which I mount preferably in the partition 28. To this end I form a bore 50 in the partition which extends downwardly to the cavity 45 and a short distance below the cavity. I then form a slightly smaller bore 51 concentric with the first and extending the rest of the way through the partition. 52 is a plug mounted in the bore 51 and supported by the annular shoulder between bores 50 and 51. The joint between this plug and the bore 51 is preferably sealed by gasket 53. Plug 52 is hollow, being threaded at its lower end to receive a conductor 54 which extends down into the sump. Conductor 54 communicates with an axial passage 55 through the plug at the top of which is a valve seat 56 disposed within the cavity 45.

In the bore 50 I mount a casing 57 which has a shoulder 58 engaging a boss on the top of the partition, and a gasket 59 to seal the joint around the casing. A central bore 60 is formed in the casing in which is slidably mounted a plunger 61 that is pressed downwardly by a coil spring 62, the upper end of which bears against an adjusting screw 63 that is threadably mounted in the casing above the bore 60. A lock nut 64 serves to hold the screw 63 in adjusted position. Plunger 61 has a conical lower extremity 65 forming a valve piece which is adapted to engage the seat 56, part of the conical surface extending into the passage 55 when the valve is closed, and part of it remaining above the seat. That part which remains above is exposed at all times to whatever pressure of liquid exists in cavity 45. In addition, I may slightly reduce the diameter of the plunger above the conical surface 65 in order to provide an annular shoulder 66 as a further surface normally exposed to the pressure in cavity 45. From this description it will be apparent that when the pressure in cavity 45 rises to a predetermined height, its action upon the exposed part of the conical surface 65 and upon the shoulder 66 will cause the plunger to rise in opposition to the spring 62. As soon as the plunger leaves the valve seat 56, that part of the plunger which was formerly enclosed by the valve seat also becomes exposed to the liquid pressure in cavity 45. Hence, after the valve is opened a reduced pressure will serve to maintain it open, and consequently the valve does not immediately close when pressure is relieved through passage 55. Valve chatter is thereby avoided.

Also, inasmuch as a reduced area of the plunger is exposed to the liquid pressure normally, the spring 62 may be smaller and of less strength than would ordinarily be required to handle a given pressure. In the event that any pressure liquid leaks past the plunger, that is upwardly along its outer wall, the oil which collects in the bore 60 can drain out through a passage 67 drilled axially through the plunger.

In Fig. 4 I have illustrated a somewhat different motor-pump unit. In this modification the motor has a lower bell 78 which, as in the first described form, is integral with a partition 71 having a flange 71' similar to and functioning in the same manner as the flange 28. In other words it is supported by ledge 27 through the intermediacy of a gasket 31. The partition 71 supports a pump housing 72, and has a passage therethrough to accommodate a shaft 73 which is common to both the motor and the pump. 74 is a pump rotor which turns with shaft 73. Liquid enters the pump from a passage 75 formed in partition 71 and is discharged through a passage 76 also formed in the partition. The pump per se forms no part of the present invention and therefore is not disclosed in detail herein. The inlet passage 75 is connected with the sump by a conductor 77, while the live liquid flowing through passage 76 is carried to the control valve 17 by a conductor 78 similar to conductor 41.

In this form of the invention I employ a pressure relief valve which is mounted in the partition in communication with the liquid delivery passage 76 and is adapted to by-pass liquid back into the sump. In this modification there is a single casing 79 which projects through the upper and lower walls of the partition and intermediate of its length consists merely of vertical ribs 80, so that liquid is free to reach the seat 81 of the valve, the upper part of the conical surface of valve piece 82, and an annular shoulder 83 on the plunger. The plunger 84 is pressed downwardly toward seat 81 by a spring 85. There is a by-pass 86 similar to by-pass 55 and a drain passage 87 similar to passage 61. The purpose and operation are the same as in the first described form of the invention.

In the foregoing description I have necessarily gone somewhat into detail in order to explain fully the particular embodiments of the invention herein illustrated, but I desire it to be understood that such detail disclosures are not to be construed as amounting to limitations except as they may be included in the appended claims.

Having thus described my invention, I claim:

1. In a hydraulic press, a housing having a vertical portion and integral lower and upper forwardly projecting horizontal portions spaced apart, said lower horizontal portion comprising a work table, a power cylinder and control valve carried in said upper horizontal portion, the lower part of said vertical portion forming a closed chamber providing a sump, a ledge extending inwardly from the sides of said vertical portion at an intermediate point in its height, a motor and pump unit supported by said ledge with the motor above the ledge and the pump therebelow, and liquid connections from said pump to said control valve and from said control valve back to said closed pump chamber.

2. In a hydraulic press, a housing having a vertical portion and integral lower and upper forwardly projecting horizontal portions spaced apart, said lower horizontal portion comprising a work table, a power cylinder and control valve

carried in said upper horizontal portion, the lower part of said vertical portion forming a closed chamber providing a sump, a ledge extending inwardly from the sides of said vertical portion at an intermediate point in its height, a motor and pump unit supported by said ledge with the motor above the ledge and the pump therebelow, and liquid connections from said pump to said control valve and from said control valve back to said closed pump chamber, the motor and pump unit having vertically aligned shaft means for direct transmission of power from the motor to the pump.

3. In a hydraulic press, a housing having a vertical portion and integral lower and upper forwardly projecting horizontal portions spaced apart, said lower horizontal portion comprising a work table, a power cylinder and control valve carried in said upper horizontal portion, the lower part of said vertical portion forming a closed chamber providing a sump, a ledge extending inwardly from the sides of said vertical portion at an intermediate point in its height, a motor and pump unit supported by said ledge with the motor above the ledge and the pump therebelow, liquid connections from said pump to said control valve and from said control valve back to said closed pump chamber, and resilient packing interposed between said ledge and the supported surface of said unit.

4. In a hydraulic press, a housing having a vertical portion and integral lower and upper forwardly projecting horizontal portions spaced apart, said lower horizontal portion comprising a work table, a power cylinder and control valve carried in said upper horizontal portion, the lower part of said vertical portion forming a closed

chamber providing a sump, a ledge extending inwardly from the sides of said vertical portion at an intermediate point in its height, a motor and pump unit supported by said ledge with the motor above the ledge and the pump therebelow, liquid connections from said pump to said control valve and from said control valve back to said closed pump chamber, and a common shaft for said motor and pump unit extending vertically through said partition.

WILLIAM C. DENISON, JR.
